UNITED STATES PATENT OFFICE

HERMAN B. CARLSON, OF NEW HAVEN, CONNECTICUT, ASSIGNOR TO SARGENT & COMPANY, OF NEW HAVEN, CONNECTICUT

WARDROBE LOCK

Application filed March 19, 1929. Serial No. 348,207.

My invention relates to a wardrobe lock and more especially to a lock for securing a pair of wardrobe doors or the like.

Generally speaking, the invention relates to improvements in locks wherein a pair of doors mounted to swing in a common opening may be simultaneously locked to one another and to an adjacent wall.

In a more specific aspect, the invention relates to a form of locking mechanism wherein latch bolts are provided at the end of a door to engage a wall of a wardrobe or the like, and at the free edge of the door to engage an adjacent door, while a common bolt operating mechanism is provided at a convenient height, the bolts and operating mechanism being carried on an interior side of the door and hidden from view.

An object of the invention is to provide a locking mechanism of the above character having a plurality of bolts, in which each bolt may be retracted independently by engagement with a strike.

A feature of the invention resides in a relatively simple form of actuating mechanism for retracting a plurality of bolts by a single operating member.

To these and other ends, the invention consists in the novel features and combination of parts to be hereinafter described and claimed.

In the drawings,

Fig. 1 is a view of a pair of doors of a wardrobe or the like having a wardrobe lock according to my invention mounted thereon;

Fig. 2 is an end view of one of the doors showing the improved lock mechanism mounted therein;

Fig. 3 is a sectional view along lines 3—3 of Fig. 2;

Fig. 4 is a sectional view along line 4—4 of Fig. 2;

Fig. 5 is a view showing the parts of the lock mechanism in a different position from that shown in Fig. 3; and

Fig. 6 is a sectional view along line 6—6 of Fig. 5.

Referring to the drawings in which I have illustrated my invention by showing a preferred embodiment of the same, the reference

numeral 10 indicates, in general, a door frame of a wardrobe or the like having hingedly mounted on the opposite sides thereof a pair of doors 11 and 12, the free edges 13 and 14 of which abut when the doors are in closed position. Seated in door 11 and flush with the inner face 15 and free edge 13 thereof, and at a convenient height from the bottom of the wardrobe, is a lock case 16 having in the inner wall 17 thereof an opening 18 for the reception of a spindle 19 extending through the opening 18 towards the exterior of the door and provided with one or more tongues 20, which are received within a similar number of recesses 21 in shank 22 of knob 23, knob 23 being mounted at the exterior of the door 13 in escutcheon 24, and being held against movement in an axial direction in escutcheon 24 by shoulder 25 bearing against the outer face 26 of escutcheon 24, and split ring 27 received in groove 28 in knob shank 22 and bearing against an interior face 29 of the escutcheon. Escutcheon 24 is held on door 13 by means of a plurality of screws 30 which pass through the door 13 from the interior thereof into the escutcheon.

Lock case 16 is provided with a cover plate 31 secured by means of screws 32 to the main body of the case 16 and passing through cover plate 31 and into door 13 are screws 33 which secure the lock case 16 to the door. Cover plate 31 is provided with an opening 34 in axial alignment with spindle 19 and mounted in opening 34 is a thumb turn 35 having a reduced end 36 received within a counterbored opening 37 in spindle 19 to hold the latter against axial movement in opening 18, outward movement of thumb turn 35 through opening 34 being prevented by shoulder 38 which bears against the interior surface of cover plate 31. Relative rotational movement of thumb turn 35 and spindle 19 is prevented by arm 39 on thumb turn 35, which is received between shoulders 40 and 41 on spindle 19.

Mounted at the upper edge of door 13 and flush with the inner surface thereof is a latch bolt case 42 having an open face applied to the recess in the door, latch bolt case 42 being secured to door 13 by suitable means, as for

example screws 43. The reference numeral 44 indicates a rod extending between case 16 and latch bolt case 42, rod 44 being supported in an opening 45 in a lower part of case 42 and having mounted on the upper end thereof a latch bolt 46, latch bolt 46 being provided with an arm 47 through which the rod 44 passes, and an opening 48 in which the end of rod 44 is received. Latch bolt 46 is constantly urged into protracted position by means of compression spring 49 mounted on and surrounding rod 44 and having one end bearing against a part of case 42, while the other end bears against arm 47.

25 Latch bolt 46 is free to move in an axial direction on rod 44 and is moved into retracted position by means of pin 50 extending transversely through rod 44 and engaging an upper face of arm 47, inward or retracted movement of latch bolt 46 being limited by post 51 on case 42. The head 52 of latch bolt 46 is preferably rectangular in cross-section and is received within a similarly shaped opening in the upper end of case 42, head 52 being provided with a beveled or inclined face 53 which cooperates with a strike 54 on the adjacent door frame to retract the bolt, strike 54 being provided with a bolt receiving opening 55 and a downwardly extending arm 56 which limits the movement of door 13 in closing.

35 The lower end of rod 44 is threaded, as at 57, and mounted on the threaded end 57 is a cross-head 58, supported between flanges 59 and 60, and connected by a pivotal stud 61 to a link 62 which is pivotally connected at 63 to arm 64 of spindle 19, movement of spindle 19 in one direction being limited by post 65 on casing 16.

40 The mechanism described up to this point is suitable for latching a door to a door casting or the like, and its operation may be briefly described as follows: Assuming the parts of the lock mechanism to be in the position shown in Figs. 3 and 4, rotation of handle 23 will rotate spindle 19 and through the medium of link 62 will cause cross-head 58 to descend, carrying latch bolt 52 with it, and withdrawing the latter from the strike receiving opening 55 in strike 54. The door is now free to open and may be swung on its hinges by means of knob 23. When the knob 23 is released, the spring 49 will return the knob 23, spindle 19, link 62, rod 44, and latch bolt 52 to their original position in which latch bolt 52 is protracted. If the door is now closed, it will be unnecessary to rotate the knob 23 in order that the latch bolt 52 may enter the opening 55 of strike 54, since the beveled edge of the bolt 52 in cooperation with the strike 54 will retract the bolt 52 against the compression of spring 49 and permit the closing of the door.

45 One of the features of the invention resides in an arrangement wherein a pair of doors

may be latched together at the same time one of the doors is latched to a door casing. As a preferred means to this end, a latch bolt 66 is mounted in case 16 between posts 67 and 68, bolt 66 having a preferably rectangular head 69 received in a rectangular opening in wall 70 of casing 16 and urged into protracted position by means of compression spring 71 mounted in a recess 72 in bolt 66 and having one end bearing against the bolt at the end of the recess, while the opposite end bears against post 73 on casing 16. The outer end of bolt 66 may be beveled in the usual manner, while at its inner end a lug 74 is provided which may be engaged by an arm 75 of bell crank lever 76, lever 76 having a substantially cylindrical pivotal bearing part 77 received in socket 78 in case 16, while the other arm 79 of lever 76 is received under cross-head 58. Bell crank lever 76 is held in socket 78 by skirt 80 which when the lock is assembled bears against flange 59.

50 It will be readily understood that as the cross-head 58 is moved in a downward direction by link 62, through the rotation of spindle 19 and knob 23, the cross-head 58 engages arm 79 of bell crank lever 76 and rotates the latter about bearing part 77, arm 75 of bell crank lever 76 engaging lug 74 on bolt 66 and retracting the latter against the compression of spring 71. Upon the handle 23 being released, springs 71 and 49 cooperate to restore the lock mechanism to protracted position. It will be noted that bolts 46 and 66 may be retracted by engagement of their respective beveled heads with the strike plates on the door frame independently, and in each instance it will be unnecessary for the latch retracting mechanism to be operated.

55 From the above description of the nature of my invention and the preferred embodiment of the same, it will be readily seen that I have provided a relatively simple form of lock mechanism wherein a pair of doors may be locked to one another and to a door frame by a single locking mechanism.

60 While I have shown and described a preferred embodiment of my invention, it will be understood that it is not to be limited to all the details shown but is capable of modification and variation within the spirit of the invention and the scope of the appended claims.

65 What I claim is:

1. In a wardrobe lock, a lock casing, a cross-head mounted in said casing, a latch bolt remote from said casing, a connection between said latch bolt and cross-head, an operating lever for said cross-head in said casing, a link connecting said lever to said cross-head, a latch bolt in said lock casing, and a bell crank lever in said casing having one arm in operative engagement with the second-named latch bolt and the other

arm in operative engagement with the cross-head, whereby upon actuation of the cross-head by the operating lever the second-named latch bolt is actuated.

5 2. In a wardrobe lock, a lock casing, a cross-head mounted in said casing, a latch bolt remote from said casing, a connection between said latch bolt and cross-head, an operating lever for said cross-head in said 10 casing, a connection between said lever and said cross-head for reciprocating the latter upon rotation of the lever, a latch bolt in said lock casing, a bell crank lever in said casing having one arm in operative engagement with 15 the second named latch bolt and the other arm in operative engagement with the cross-head, whereby on actuation of the cross-head by the operating lever the second named latch bolt is actuated.

20 3. In a wardrobe lock, a lock casing, a cross-head mounted in said casing, a latch bolt remote from said casing, a connection between said latch bolt and cross-head, an operating lever for said cross-head in said 25 casing, a link connecting said lever to said cross-head, a latch bolt in said lock casing, and means in said casing in operative engagement with the second named latch bolt and the cross-head, for retracting the second 30 named latch bolt upon actuation of the cross-head.

4. In a wardrobe lock, a lock casing, a cross-head mounted in said casing, a latch bolt remote from said casing, a connection between 35 said latch bolt and cross-head, an operating lever for said cross-head in said casing, a connection between said lever and cross-head for reciprocating the latter upon rotation of the lever, a latch bolt in said lock 40 casing, and means in said casing in operative engagement with the second named latch bolt and the cross-head for retracting the second named latch bolt upon reciprocation of the cross-head.

45 In witness whereof, I have hereunto set my hand this 16th day of March, 1929.

HERMAN B. CARLSON.
